United States Patent Office

Des. 221,702
Patented Aug. 31, 1971

221,702

BOAT UPPER SHELL

Edward W. Peterson, Bannockburn, Ill., assignor to
Silverline, Inc., Moorhead, Minn.

Filed June 29, 1970, Ser. No. 23,714

Term of patent 10 years

Int. Cl. D12—16

U.S. Cl. D71—1

Fig. 1.

Fig. 2.

Fig. 3.

Fig. 4.

Fig. 5.

FIG. 1 is a rear perspective view of a boat upper shell showing my new design;

FIG. 2 is a top plan view thereof;

FIG. 3 is a side elevation view thereof;

FIG. 4 is a front elevation view thereof; and

FIG. 5 is a rear elevational view thereof.

The boat hull shown in broken lines in FIGS. 1, 3, 4 and 5 is included for illustrative purposes only, and the opposite side of the boat upper shell is a mirror image of FIG. 3.

I claim:

The ornamental design for a boat upper shell, as shown and described.
